UNITED STATES PATENT OFFICE.

FREDERIC E. BERTRAND, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-FITTING MACHINE.

1,350,354.

Specification of Letters Patent. Patented Aug. 24, 1920.

Application filed March 10, 1916. Serial No. 83,253.

To all whom it may concern:

Be it known that I, FREDERIC E. BERTRAND, a citizen of the United States, residing at Lynn, in the county of Essex and State of Massachusetts, have invented certain new and useful Improvements in Sole-Fitting Machines; and I do hereby declare the following to be a full, clear, and exact description of the invention, such as will enable others skilled in the art to which it appertains to make and use the same.

This invention relates to machines for operating on shoe soles and like articles, and more specifically to sole channeling machines of the general type shown in my prior patents, such for instance, as Patent No. 1,030,704, granted June 25, 1912.

Machines of this character are designed to perform certain operations on a sole blank, generally termed "sole fitting," necessary to prepare it for attachment to the upper of a shoe, and the present invention has for its general object to improve the machines of this type. Stated more specifically, the invention aims to increase the life of machines of this type and to relieve the operative of some of the care and attention which is now required of him in using the machines now on the market.

To these ends the invention resides in certain novel combinations and arrangements of parts, the advantages of which will be obvious to those skilled in this art, and the various features of which will be readily understood from the following description, reference being made to the accompanying drawings, in which;

Figure 1 is a view, in side elevation, of an insole channeling machine including mechanism embodying the invention in its preferred form;

Fig. 2 is a horizontal, sectional view on approximately the plane indicated by the line 2—2, Fig. 1; and

Fig. 3 is a front elevation of certain of the parts shown in Fig. 1 which relate to the present invention, this view being largely diagrammatic and omitting the adjacent parts of the machine.

In the embodiment of the invention illustrated in the drawings the machine is provided with a work supporting table 2 on which the sole S (Fig. 3) is positioned for

the operation thereon of the tools with which the machine is equipped. This table is normally held in the position in which it is shown in Fig. 1, but is connected with a treadle, as illustrated in my prior Patent No. 1,023,801, dated April 23, 1912, by means of which it may be lowered to permit the insertion or removal of the sole. Tools of any character suited to the requirements of the operations to be performed on the sole are mounted in suitable position in the machine head, and include a channeling knife 4. Since the particular tools employed, and the operating mechanisms for them, form no part of the present invention, they will not be specifically described herein, but reference should be made to my prior patents hereinbefore referred to for a detailed description thereof.

The sole fitting tools are operated through mechanism that is supported by the frame 10 and which includes a driving mechanism 75 comprising a shaft 12 rotatably mounted in suitable bearings carried by the frame 10, a loose pulley 14 rotatable on said shaft and constituting the driving member for the machine, and a clutch member 16 which is 80 keyed to the shaft 12 but is slidable along the shaft into and out of engagement with a clutch face formed on the pulley 14. A coiled spring 18, encircling the hub of the clutch member 16 urges this member toward 85 the pulley. It is obvious that when the clutch member 16 is out of engagement with the pulley 14 the machine will be rendered 90 inoperative, but when the members 14 and 16 are engaged, the driving mechanism then 95 becomes operative to rotate the shaft 12 and operate the tool or tools with which the machine is equipped.

The clutch mechanism just described, and consequently the driving mechanism, is under the control of a mechanism which includes a feeler that engages the sole when it is positioned on the table 2 in readiness for the tools to operate it. This clutch controlling mechanism includes a reversed or 100 inverted toggle mechanism which is duplicated at each side of the machine. Two parallel toggle arms or links 20 are mounted on opposite sides of the frame 10 (see Fig. 2) and are both pivotally connected at their rear 105 ends to a shoe 22 that is located in a periph-

eral groove formed in the clutch 16, so that the clutch member 16 can rotate freely within the shoe. These two arms 20 are pivotally connected at their forward ends to 5 the forward end of a U-shaped toggle link 24, which straddles the frame 10 and is pivoted at 26 on a stationary part of the frame, as clearly shown in Fig. 2. A bridge piece 28 connects the forward ends of the 10 two arms of the link 24. A tension spring 30, connected at one end to a pin projecting from the frame 10 and at its opposite end to one of the lever arms 20, acts through the toggle links 20 and 24 in a direction 15 tending to break the toggle and, consequently, to slide the clutch member 16 toward the pulley 14. This spring thus aids the coiled spring 18.

In order to straighten the toggle and 20 thus move the clutch member 16 away from the pulley 14, a power driven mechanism is provided which is best shown in Fig. 3. This mechanism consists of an eccentric 32, fast on the shaft 12 and therefore constantly 25 driven while the machine is in operation; an eccentric strap 34 arranged to be oscillated by said eccentric; a bell crank lever 36 fulcrumed on the machine frame at 38 and having one arm pivoted to said eccentric strap; and a link 40 pivoted to the opposite arm of said bell crank lever. The free end of this link 40 is connected by another link 42 to the free end of an arm 44 depending from a rock shaft 46 fulcrumed 35 in the machine frame. The link 40 carries at its upper end a hook 48 (Fig. 3) which at certain times is allowed to engage a lug 50 projecting from the forward end of the toggle link 24, and this engagement is controlled by a depending feeler 52 which is positioned vertically over the table 2 and is supported for movement normal to the table by two parallel links 47 and 56. The link 47 is fixed on the rock shaft 46 while 45 the link 56 is pivoted to the machine frame.

It will now be clear from an inspection of Fig. 3 that, when the machine is in operation with the shaft 12 rotating, the eccentric 32 will operate through its eccentric strap 34 and the bell crank lever 36 to oscillate the upper end of the link 40 in substantially a vertical plane. This oscillating movement obviously carries the hook 48 up and down past the lug 50, but while the feeler 52 is resting on a sole on the table 2, the path of movement in which it is constrained to operate by the parts 47, 46, 44 and 42 is beside the lug 50. As soon, however, as the sole S is removed from under the feeler 52, this feeler drops under the influence of gravity 55 toward the table 2 (see Fig. 1), thus swinging the lower end of the arm 44 in a counter-clockwise direction and causing the hook 48, on its next upward movement, to slide over 60 the upper edge of the lug 50 and to carry

this lug downwardly on its next downward stroke. This action moves the toggle 20-24 from the broken position in which it is shown in dotted lines in Fig. 1 into a straightened position, as indicated in full 70 lines in said figure, thus overcoming the action of the springs 30 and 18 and sliding the clutch member 16 along the shaft 12 out of engagement with the pulley 14. This action, of course, disconnects the shaft from 75 the driving pulley 14 and interrupts the operation of the driving mechanism.

The table 2 is depressed to remove the sole from it and to place another sole in position thereon, and when this table next 80 rises, carrying a new sole up under the lower end of the feeler 52, this member is raised and operates through the arms 47 and 44 and the link 42 to move the hook 48 out of engagement with the lug 50 and thus permits the spring 30 to break the toggle again, and consequently to move the clutch member 16 into engagement with the pulley 14 and start the machine into operation. The machine, of course, will continue in operation 90 until the work is removed from engagement with the feeler again, when the cycle of operations to stop the machine will be repeated.

A brake is provided for the purpose of 95 stopping the machine quickly when the clutch is thrown out. This brake consists of a stationary bracket or shoe 60, mounted on the machine frame, as best shown in Fig. 2, and provided with an inner, conical face with which a correspondingly shaped face on the end of the clutch member 16, opposite to that which engages the pulley 14, is adapted to engage. This brake is mounted immediately in front of the clutch 100 so that it is engaged by the clutch member 16 immediately said member is freed from the driving pulley 14. Since the clutch member 16 is keyed to the shaft 12, its engagement with the brake rapidly retards 105 and practically instantaneously stops the rotation of the shaft 12. Inasmuch as the clutch member 16 is under the control of the feeler 52, the position of this feeler determines whether the driving member 14 or 110 the brake 60 shall be operatively connected to the shaft 12 at any instant.

It is obvious that the mechanism above described renders the starting and stopping of the machine entirely automatic and dependent merely upon the presentation of the work to the tools of the machine. The operative thus is relieved of the care and attention which otherwise would be required of him to start and stop the machine. At 120 the same time the useless wear on the running parts of the machine, which otherwise would be occasioned by the idle running of the machine is eliminated and the life of the machine is correspondingly increased. 130

While the embodiment of the invention at present preferred has been described above for the purpose of clearly explaining the nature of the invention, it is obvious that 5 the invention is not limited to embodiment in the specific form shown, but that it may take many forms without departing from its scope as defined in the appended claims. It will also be understood that the invention 10 is not limited in application to the specific type of machine shown.

What is claimed as new is:—

1. An insole channeling machine, having in combination, a vertically movable sole 15 supporting table, a channeling tool arranged to operate on a sole supported on said table, a device mounted to engage the upper face of said sole, driving mechanism for said tool and connections whereby said device is 20 enabled to control the operation of said driving mechanism.

2. An insole channeling machine, having in combination, a channeling tool, a sole support movable toward and from said tool, 25 driving mechanism, a feeler mounted to engage the sole and to be moved thereby when the sole is moved by said support, and connections whereby a movement of said feeler produced by its engagement with the sole 30 modifies the operation of said driving mechanism.

3. A machine for operating on soles and the like, having in combination, driving mechanism including a clutch, toggle mechanism 35 arranged to throw said clutch into or out of operation, a spring tending to maintain said clutch in operation, a member constantly driven while the machine is in operation and arranged to act through said 40 toggle mechanism to throw the clutch out of operation, and a work engaging feeler connected with said driven member and controlling its operation on said toggle mechanism.

4. A machine for operating on soles and the like, having in combination, driving mechanism including a clutch, a toggle mechanism arranged to throw said clutch into or out of operation, a spring tending 50 to maintain said clutch in operation, a member constantly driven while the machine is in operation and arranged to engage said toggle mechanism and move it to throw the clutch out of operation, and a work engaging feeler connected with said driven member and controlling its engagement with said toggle mechanism.

5. A machine for operating on soles and the like, having in combination, a rotary 60 shaft, a driving member loose on said shaft, a coöperating clutch member movable longitudinally of said shaft, a spring tending to hold said clutch member in engagement with said driving member, an inverted toggle mechanism connected with said clutch

member and including two pairs of toggle links mounted on opposite sides of said shaft, a member constantly driven while the machine is in operation operative to engage 70 said toggle mechanism and move it in a direction to overcome the action of said spring, and a work engaging feeler connected with said driven member and controlling its engagement with said toggle mechanism.

6. A machine for operating on soles and the like, having in combination, a rotary shaft, a driving member loose on said shaft, a coöperating clutch member movable longitudinally of said shaft, a spring tending to 80 move said clutch member in one direction, power driven means connected with said member and operative to overcome the action of said spring and move the clutch member in the opposite direction, a work 85 engaging feeler controlling the action of said power driven means, and a brake arranged to be rendered operative or inoperative to retard the rotation of said shaft by the connections controlled by said feeler. 90

7. A machine for operating on soles and the like, having in combination, a rotary shaft, a driving member loose on said shaft, a coöperating clutch member movable longitudinally of said shaft, a spring tending to 95 move said clutch member in one direction, power driven means connected with said member and operative to overcome the action of said spring and move the clutch member in the opposite direction, a work engaging feeler controlling the action of said power driven means, and a brake with which the clutch member engages when it is moved away from said driving member. 100

8. A machine for operating on soles and the like, having, in combination, driving mechanism including a clutch, a controlling means for said clutch including means to normally maintain the clutch in a driving position, a clutch shifting mechanism, power 105 means for operating said clutch shifting mechanism, devices for connecting the power means with said mechanism, and a work engaging feeler constructed and arranged to make said connecting devices effective when the work is withdrawn from engagement therewith. 110

9. A machine for operating on soles and the like, having, in combination, a driving member; a brake member; a clutch member 120 shiftable into engagement with said driving member or brake member; a sole engaging feeler constantly engaging with the sole when said clutch and driving members are in engagement; a sole support; means for 125 relatively moving said support and feeler toward and from each other; and connections between the feeler and clutch member, controlled by the engagement and disengagement of the feeler and sole, for shift- 130

ing the clutch member into engagement with the driving member or brake member respectively.

10. A sole fitting machine, having, in combination, a tool for operating upon the work, a movable support to position the work for the operation of said tool, means to move the support toward and from the tool to enter and remove the work, driving means for 10 operating the tool, a source of driving power, means for connecting and disconnecting the driving means and the source of power, a movably mounted feeler opposite the support arranged to follow the movement of the support, and devices connecting said feeler with said last named means whereby the operation of the tool is controlled by said feeler.

11. A sole fitting machine, having, in combination, a tool for operating upon the sole, a work support, means for feeding said sole, a source of power for said sole feeding means, interruptable connections between the source of power and the feeding means, 25 and a device for engaging the face of the sole constructed and arranged to control the engagement of said connections and maintain said feeding means in operation whenever work between the tool and support is 30 engaged by the tool.

12. A sole fitting machine, having, in combination, a clutch, a driving member, a spring for normally connecting the clutch with the driving member, mechanism including a lock for holding the clutch in disconnected position with relation to said driving member when no work is in the machine, a movable work engaging device, and means connected with the work engaging 40 device and controlled by its movement for unlocking the lock when said device is engaged by work entered in the machine and locking it again when the work is removed.

13. A sole fitting machine, having, in combination, a tool for operating upon the work, mechanism for feeding the work, means for supporting the work and movable to bring the work in contact with the tool, a source of power for operating the work feeding mechanism, a feeler constructed and arranged to be engaged and moved by the work during its approach toward the tool, and connections between the feeler and the source of power by which the work feeding mechanism will be set into operation when the work is brought into contact with the tool.

14. A sole fitting machine, having, in

combination, a tool for operating upon a sole, a sole support, means to relatively move the tool and support to enter and withdraw a sole from operative position, a feeler mounted opposite the support to engage the face of the sole, means for feeding the sole, a source of power, and connections 65 between the feeler and the source of power by which the relative movement of the support and tool to enter soles into and remove them from operative position will control the operation of the sole feeding means. 70

15. A sole fitting machine, having, in combination, a tool for operating upon a sole, means for feeding the sole, means for driving the feeding means, operating mechanism therefor including a hook arranged 75 to be continuously actuated while the machine is running, and a feeler arranged to be controlled by the presence or absence of the sole for shifting said hook into and out of position for operating the starting and stopping mechanism.

16. A channeling machine having, in combination, feed mechanism, a sole support movable relative to said feed mechanism, and means controlled by the movement of 85 said support for connecting and disconnecting the power for actuating the feed mechanism.

17. A channeling machine having, in combination, channeling devices, a sole support, 90 sole feeding means, mechanism for operating the feeding means, means relatively to move the channeling devices and support to free a sole being operated upon, and means controlled by said relative movement for 95 stopping the operation of said mechanism.

18. A channeling machine having, in combination, power driving mechanism, channeling devices, a sole support, movable toward and from the channeling devices, and 100 means controlled by the movement of said support for connecting and disconnecting the power driving mechanism.

19. A channeling machine having, in combination, channeling devices, a sole support, 105 sole feeding means, mechanism for operating the feeding means, means for relatively moving the channeling devices and the support to draw them apart in removing the sole, and means controlled by the relative 110 movement of the channeling devices and the support to stop the said mechanism when the channeling devices and the support are moved apart, and to lock said mechanism in its position of rest.

FREDERIC E. BERTRAND.

It is hereby certified that in Letters Patent No. 1,350,354, granted August 24, 1920, upon the application of Frederic E. Bertrand, of Lynn, Massachusetts, for an improvement in "Sole-Fitting Machines," an error appears in the printed specification requiring correction as follows: Page 1, line 99, after the word "operate" insert the word *on*; and that the said Letters Patent should be read with this correction therein that the same may conform to the record of the case in the Patent Office.

Signed and sealed this 19th day of October, A. D., 1920.

[SEAL.]

M. H. COULSTON,

Acting Commissioner of Patents.

Cl. 12--17.
